Inventor:

UNITED STATES PATENT OFFICE

WILLIAM G. HARTWIG, OF CHICAGO, ILLINOIS, ASSIGNOR TO RAILWAY UTILITY COMPANY, OF CHICAGO, ILLINOIS, A CORPORATION OF ILLINOIS

ELECTRIC TERMINAL CONNECTER

Application filed April 2, 1932. Serial No. 602,711.

This invention relates to improvements in electrical terminal connecters and particularly to such connecters as are used in association with electric car heaters as disclosed in my application, Serial No. 597,101, filed March 7, 1932.

It is an object of the present invention to provide a self-locking binding post for clamping a wire to an electrical terminal extension.

It is further an object of the present invention to provide a stamped metal body member adapted for clamping an end of the terminal extension and adapted to form a seat against which the wire is clamped by the head of a threaded binding screw, the metal body member having resilient fingers in thrust engagement with the threaded portion of said screw.

Further objects and advantages of the present invention will be more readily apparent from the following description taken in connection with the attached drawing, in which

Figure 1 is a plan view partially in section showing a pair of terminal extensions and a pair of self-locking binding posts associated therewith;

Figure 2 is a broken section taken transversely of Figure 1;

Figure 3 is an end view of the metal body member forming a part of the terminal connection;

Figure 4 is a top view of the metal body member showing the binding screw in section;

Figure 5 is a vertical section of the metal body member showing the association therewith of the binding screw;

Figure 6 is a view similar to Figure 5 except that a wire and a terminal extension are shown connected therewith, and

Figure 7 is a bottom view of the metal body member.

The improved design of electrical lead-in and connections thereto is shown in the drawing in association with a portion of a car heater. The bracket 10 supports one end of a resistance unit 12 which is attached by screw bolt 14 and nut 16. The resistance

unit is spaced from the bracket 10 and insulated therefrom by bushing 18 and a second bushing 20 which passes through the end of resistance unit into the bushing 18 and serves to insulate the connection from the screw bolt 14. The resistance unit has a pair of spaced contacts 22-24, each of which is provided with an upstanding threaded stud 26. The terminal extensions 28 and 30 are formed of thin pressed metal, channel-shaped in cross section, having depending flanges 32. The extensions are secured to the contact terminals of the resistance unit through nuts 34 which are received within openings at the ends of the extensions 28 and 30. The nuts 34 are peened over at their upper ends as shown at 35 to securely hold the ends of the extensions 28 and 30. The terminal extensions 28 and 30 pass through an insulating block 36 which is supported by the plate 38 of the heater and by the wall 40 which is spaced therefrom.

The wire connections to the terminal extensions 28 and 30 are made through the provision of a novel form of clamping device, as shown in detail, Figures 3 to 7. A pressed metal clamping piece, generally designated 42, is formed with a confining seat 43 for the connecting wire 44. The seat 43 is partially surrounded by an arcuate upstanding wall 45. The seat 43 has an opening 46 for the passage of the screw bolt 47. The screw bolt 47 has an enlarged head 48 adapted to tightly clamp the bent end of the wire 44 against the clamping seat 43. The bottom part 49 of the clamping piece 42 is bent into position substantially parallel to but spaced from the bottom side of the wire clamping seat 43, as shown by the space 50 in Figure 5. The metal piece 42 is therefore substantially U-shaped in form. The space 50 is adapted to receive the channel-shaped end of one of the terminal extensions, such as 28. The width of the part 49, as shown in the bottom view of Figure 7, is such as to closely fit between the flanged edges 32 of the extension 28. A pair of tongues 51-51 are pressed out of the part 49 and are adapted to bear at their ends 52 in engagement with

the threaded portion of the screw bolt 47. As shown in Figure 6 the tongues 51 are in opposed relation and will have the effect of a toggle as the screw bolt is tightened and will assist in securely holding the bolt against loosening. The screw bolt or binding post is in threaded engagement with an opening of the terminal extensions.

It will therefore be understood that I have disclosed a unitary self-locking binding post in which by simply tightening the screw bolt 47 the connecting wire is clamped tightly upon its seat and the terminal extension is clamped tightly between the top and bottom walls of the clamping piece 42.

I claim:

1. In combination, a threaded binding post having a wire clamping head, a pressed metal electrical connector having a cup-shaped seat for receiving an end of the wire adapted for clamping thereto by the head of the binding post, said pressed metal member having a pair of resilient fingers in opposed relationship adapted to bear in thrust engagement with the threaded portion of said binding post for locking the parts in engagement.

2. An electrical connector for securing a wire to a metallic terminal extension comprising, a pressed metal member substantially U-shaped in form, adapted to fit over an end of the terminal extension, the upper part of said pressed metal member forming a cup-shaped seat for the securement of the wire thereto and a threaded binding post having an enlarged wire clamping head adapted to extend through an opening in the upper part of said pressed metal member and through an opening in said terminal extension, said pressed metal member having a pair of resilient fingers pressed out of the lower part thereof in thrust engagement with the threaded portion of said binding post on the lower side of said terminal extension.

3. An electrical connector between a wire and a substantially channel-shaped metallic terminal extension comprising, a substantially U-shaped metal member, one leg of which is formed to fit into the channel-shaped portion of said terminal extension, the other leg of which is adapted to lie on the other side of said terminal extension, a threaded binding post adapted to extend through both legs of said pressed metal member and through an opening of said terminal extension, said binding post having an enlarged head for clamping an end of the wire against the upper face of the pressed metal member and the other leg of said pressed metal member having a pair of resilient fingers adapted to bear in thrust engagement against the threaded portion of said binding post.

4. An electrical terminal connector for se-

curing a wire end to a channel-shaped terminal extension comprising, a substantially U-shaped pressed metal member, one leg of which is formed with a pair of outwardly pressed and oppositely disposed resilient fingers, said leg being adapted to fit into the channel-shaped portion of said terminal extension from one end thereof, the other leg of said U-shaped member being adapted to clamp against the other side of said terminal extension, said last-mentioned leg having an opening therein, a threaded binding post having an enlarged wire clamping head adapted to freely pass through the opening in said last-mentioned leg whereby the wire end may be clamped by the head of said binding post against said leg, said resilient fingers of the other leg being adapted to bear in thrust engagement against the threaded portion of said binding post on the other side of said terminal extension whereby said terminal extension is tightly clamped between the U-shaped legs of said pressed metal member.

Signed at Chicago, Illinois, this 30th day of March, 1932.

WILLIAM G. HARTWIG.
